BOTTLED DRINK VENDING MACHINE CASE

Charles G. Meyer, Kansas City, Mo., assignor to
The Vendo Company, Kansas City, Mo., a cor-
poration of Missouri

Application July 16, 1951, Serial No. 15,880

Term of patent 14 years

(Cl. D52—3)

To all whom it may concern:

Be it known that I, Charles G. Meyer, a citizen of the United States, residing at Kansas City, in the county of Jackson and State of Missouri, have invented a new, original, and ornamental Design for a Bottled Drink Vending Machine Case, of which the following is a specification, reference being had to the accompanying drawing, forming part thereof.

Fig. 1 is a perspective view of a bottle drink vending machine case, showing my new design.

Fig. 2 is a side elevational view thereof; and
Fig. 3 is a top plan view thereof.

I claim:

The ornamental design for a bottled drink vending machine case, as shown.

CHARLES G. MEYER.
